GOLF BALL TEEING DEVICE

Joe Mozel, Portland, Oreg.

Application May 28, 1947, Serial No. 750,903

7 Claims. (Cl. 273—33)

1

This invention relates to golf ball teeing devices and is particularly related to golf ranges and indoor practice courts.

The primary object of this invention is to provide a lifting mechanism for lifting the golf ball from a low level to a higher level, said lifting mechanism placing the golf ball in a runway from where it is picked up by a teeing device. This said mechanism is so designed that it can lift and tee up any type of golf ball, regardless of size, shape or condition.

A further object of the invention is to keep this lifting mechanism within the case or frame of the golf ball teeing device.

A still further object of the invention is the provision of a timed relation between the operation of the lifting device and the teeing mechanism.

And a further object is to provide electric controls within the golf ball teeing device for co-ordinating the operation of the lifting mechanism with the teeing mechanism, the same being controlled by the golf balls within the device.

These and other incidental objects will be apparent in the drawings, specification and claims.

Referring to the drawings:

Figure 1 is a plan view of my new and improved golf ball teeing device.

Figure 2 is a side elevation taken on line 2—2 of Figure 1.

Figure 3 is a sectional elevation taken on line 3—3 of Figure 1.

Figure 4 is a fragmentary sectional detail taken on line 4—4 of Figure 2.

Figure 5 is an end sectional view taken on line 5—5 of Figure 1.

Figure 6 is an end sectional view taken on line 6—6 of Figure 1.

Figure 7 is a fragmentary side view taken on line 7—7 of Figure 6 looking into the cam operated switches.

Figure 8 is a fragmentary sectional detail view of the golf ball teeing mechanism in partially raised position.

Figure 9 is a diagrammatical wiring diagram of the electric controls.

In the drawings:

My new and improved golf ball teeing device consists of a frame 1, comprising a side frame 2 and an oppositely disposed side frame 3, both sides being connected together by cross members 4. A special golf ball receiving and dispensing chamber 5 forms part of a cast frame 6 or bridge, said bridge in turn is mounted to the side frames 2 and 3 best illustrated in Figures 1 and 5.

Leading into the dispensing chamber 5 is a ball guideway 7, whose end 8 registers with the end 9 of a ball guideway 10 formed within the

2

side frame 3 of the teeing device. The guideway 10 consists of an annular track 11 beginning at the point 12 and continuing in a circle, best illustrated in Figure 3, to the point 13. The guideway 10 has an annular flange 14 forming part of the side wall 15 of the frame 3, best indicated in Figure 6. The inner side of the guideway has a removable closure plate 16, which provides an inner side wall for the guideway 10.

An opening 17 is provided in the side wall 15 of the frame 3 of the machine which permits the entry of the golf ball 18 from any suitable delivery chute 19, indicated in broken lines in Figure 4. An electric motor 20 is mounted to the brackets 21 by a motor mount 22. The brackets 21 are cast integral with the frame 2, providing a rigid support for the motor mount assembly. The shaft 23 and worm 23' of the motor drives a worm wheel 24, which is mounted to a countershaft 25, which in turn drives the operating shaft 26 through the gears 27 and 28.

The operating shaft 26 is journalled within a bearing 29 of the motor mount 22 and a bearing 30 in a sleeve 31 forming part of the side frame 3. The shaft 26 is divided by a universal coupling 32. Fixidly mounted to the shaft 26 is an arm 33, the outer end of which terminates in fingers 34 and 35 that extend at substantially right angles to each other for engaging and lifting the golf ball 18 around the guideway 10 and delivering the ball into the guideway 7 leading to the golf ball receiving and dispensing chamber 5. This operation will be more fully described later.

I will now describe the construction and operation of the automatic electric golf ball teeing mechanism, which consists of a rubber tee 36, which is fixedly secured to the vertically mounted rod 37, which is slidably mounted within the guide 38, as best illustrated in Figure 5. The guide 38 forms part of the framework 39 which is slidably mounted to the vertical guide member 40 by the outwardly extending brackets 41 terminating in bearings 42 which work freely on the guide 40.

The upper end of the guide 40 is fixedly mounted at 43 to the frame or bridge 6 and its lower end is fixedly mounted at 44 to the cross frame 45, which is secured to the side frames 2 and 3 of the device, best illustrated in Figures 3 and 5. The vertical position of the tee assembly is governed by the lever arm 46 which is fixedly mounted to the cross shaft 47, which is journalled at one end within a bearing 48 forming part of the side plate 16 of the guide 10 and at the other end in a bearing 49 fixed to the side frame 2.

A spring 50, having coils 51, is mounted to the cross shaft 47 and has one of its ends formed into a yoke 52, which bears on the underside of the lever arm 46, and its opposite free ends 53 selectively seated in the notches 54 formed in

the frame 1, best illustrated in Figures 1, 3 and 6. By having a series of notches 54, the tension of this spring can be varied to meet different operating conditions.

A link 55 is pivotally connected at 56 to the lever arm 46 and to the bracket 57 of the framework 39, and raises and lowers the framework and tee 36 when the operating arm 46 is moved. Cranks 58 are fixedly mounted to the operating shaft 26 and have a roller 59 journalled between their outer ends. When the operating shaft 26 is revolved, in the direction of the arrow (Fig. 3), the cranks 58 are revolved therewith. The roller 59 will contact the upper side of the arm 46, forcing it downwardly against the tension of the spring 50 and thereby lowering the frame 39 of the tee 36 to the position illustrated in Figure 2. After the cranks start to move up, the spring 50 will raise the lever arm 46 and the tee back to the teeing position. The height of the tee is governed by the stop 60 which engages the lever 46, best illustrated in Figures 3 and 8.

The stop 60 consists of a plunger 61 slidably mounted within the tubular member 62 which is threaded within the frame 6 at 63 and locked by the locking nut 63'. A cross shaft 64 is journalled at its one end within the bracket 65, which forms part of the frame 6, and at its other end within the side frame 2. A crank 66 is fixedly mounted at one end of the shaft 64 and is connected to the plunger 61 by the link 67. An operating lever 68 is formed on the opposite end of the shaft 64 and extends up above the top of the frame of the machine so that it can be adjusted by the player.

A brake is applied to the shaft 64 by the adjusting screw 69, which bears against the shaft to the desired amount of friction so that when the lever 68 is moved this friction will hold the shaft from turning in either direction. By moving the lever 68 in either direction it will raise or lower the plunger 61 and the stop 60, through the shaft 64, the crank arm 66 and link 67, to any desired position, and thereby adjust the elevation of the operating lever 46 and the tee 36.

When a ball 18 rolls from the delivery chute 19 through the opening 17 into the guideway 10, it lands upon the plate 70, which is movably positioned above the surface of the trackway 11. The plate 70 is carried by an arm 71 that is fixed to a stub shaft 72, which is pivotally mounted in a bearing 73 that is supported by the frame 3. When the golf ball is resting on the plate 70, the opposite end 74 of the arm 71 is raised into engagement with the operating member 76 of a switch 75. When the switch 75 is thus actuated it will be closed across its contacts 75A, as may best be seen in Fig. 9.

When a golf ball is resting on the tee 36, the switch 77 will be opened, due to the weight of the ball lowering the rod 37 which rests on the switch operating bar 78, best illustrated in Figs. 5 and 9, and when the ball is removed from the tee, the plunger or rod 37 will be raised by the spring action of the operating bar 78. The raising motion of the operating bar 78 closes an electric circuit through the switch 77, referring to the wiring diagram of Fig. 9. If the switch 77 is closed by the removal of a ball from the tee 36, and the switch 75 is closed across its contacts 75A, by a ball resting on the plate 70, electric energy will then flow from the supply line 79 through the electric motor 20, conductor 80, through the switch contacts 75A of the switch 75, electric conductor 81, through the switch 77

and to the main supply line 82. This will cause the motor to revolve the operating shaft 26, rotating the arm 33 in the direction of the arrow, raising the golf ball 83 around the guideway 10 and into the guideway 7 to the golf ball receiving and dispensing chamber 5. By the time this ball reaches this chamber, the tee 36 will be in the lower position, as indicated in Figure 2, through the operation of the crank 58—59 depressing the arm 46.

Referring to Figure 7, the cam 84, which is fixedly mounted to the outer end of the operating shaft 26, will have travelled in the direction of the arrow (Fig. 9), breaking contact with the switch operating bar 85, which will cause the switch 86 to close an electric circuit through the electric motor 20, conductor 87, conductor 88 and back to the main line 82. This is a carry over switch and maintains the electric circuit closed through the motor after the tee 36 begins to raise to pick up the golf ball within the dispensing chamber 5, and, because of the weight of the ball, opens the switch 77. Therefore the switch 86 will maintain the motor in operation until the cycle is completed and the cam 84 again contacts the bar 85, opening the switch 86 and stopping the motor. On each cycle of operation the cam 84 contacts the operating switch bar 89 of the switch 90, this closes an electric circuit through the conductor 91 through the switch 90. A recording meter 92 is located adjacent the golf teeing machine through the conductor 93 to a recording meter 94 which is located remotely from the teeing device, and is usually in an office connected with the golf course where the golf ball teeing devices are installed.

When there are no balls on the plate 70, both the attendant at the office and the player at the tee will be informed of this fact in the following manner. The switch 75 is a double circuit switch and when the operating bar 71 is allowed to raise, due to the absence of a golf ball on the plate 70, the switch bar 76 will open the contacts 75A and close the contacts 95. This completes a circuit through the conductor 96 from the main line through the switch contacts 95, through the indicating light 97 located adjacent the golf ball teeing device and through the conductor 98 and indicating light 99 located in the office so that both the player and the office attendant will know that the machine is out of golf balls. When there is no golf ball on the plate 70 the plate will be raised by the switch bar 76 of the switch 75, and at the same time this switch will open the motor circuit above described, preventing operation of the machine.

Referring to Figure 8, I have provided a one way latch or stop 100, which is pivotally mounted at 101 to the side of the ball dispensing chamber 5. It will be noted that a golf ball can be raised through this latch but a ball cannot drop down through the said latch as indicated by the dotted position of the latch. This is a safety feature preventing the jamming of a ball in the machine. A ball can only be raised and never dropped down into the chamber.

The feature which I am desirous of covering primarily in this application is the operation of the ball lifting feature consisting of the arm 33 and the guideway 10 for raising the ball from a lower level to a higher level within the golf ball teeing device. I already have a Patent Number 2,295,599 issued on the operation of the tee in general, but I have rearranged the mechanisms slightly from the organization disclosed by this

patent to incorporate the method I have shown and described for raising the ball and putting it into the golf ball dispensing chamber of the machine.

I do not wish to be limited to the exact mechanical construction, as other mechanical equivalents may be substituted still coming within the scope of my claims.

What I claim is:

1. A golf ball teeing device which comprises a ball playing station, a ball loading station, a tee movable between a loading position to receive a ball at said loading station and a teeing position at said playing station, a ball feeding station, a ball feeding member movable to feed a ball from said feeding station to said loading station, means responsive to the lack of a ball on the tee at the playing station and the presence of a ball at the feeding station for moving said feeding member and said tee in timed relation to feed a ball from said feeding station to tee-up said ball at the playing station, a remote operator's station, and means operative by the lack of a ball at the feeding station for signalling at the tee and at the operator's station the lack of a supply of balls at said feeding station.

2. A golf ball teeing device which comprises an open-sided cup for receiving and positioning a ball to be teed-up, an opening in the bottom of said cup, a tee movable vertically through said cup and the opening therein, said tee being movable between a loading position to load a ball that is in said cup and a teeing position above said cup, a pivotally mounted lever connected at one end to said tee and biased upwardly to raise said tee to teeing position, a feeding station to which balls may be supplied, a guideway from said feeding station to said open side of said cup, a ball feeding member movable longitudinally through said guideway to feed a ball from said station to said cup, said feeding member comprising a cam member that is positioned to depress said lever to lower said tee upon the operation of said feeding member, and means for advancing said feeding member through its feeding movement and for vertically moving said tee between its positions in timed relation.

3. A golf ball teeing device which comprises a tee that is movable to and from a ball loading station and a ball playing station, a ball feeding member for moving a ball from a ball feeding station to the ball loading station, means operative by a ball at the feeding station for moving said feeding member to move the ball to said loading station, and means subject to the weight of a ball on said tee to control the operation of said first-mentioned means.

4. A golf ball teeing device which comprises, in combination, a cup forming a loading station, a tee, means supporting said tee for movement to and from the loading station in said cup and a playing station above said cup whereby said tee may receive a ball at said loading station and be raised to a position for playing the ball, a stop pivoted at the side of said cup for vertical movement, said stop extending inwardly from the top of said cup to be pivoted upwardly by a ball on said tee to permit the passing of said ball, means on said stop to limit its pivotal movement to prevent its passing over center and permit its dropping by gravity after the ball is past, and means on the cup to horizontally position the stop to block the mouth of the cup to prevent the ball from falling therein.

5. A golf ball teeing device comprising a frame, a golf ball dispensing chamber within said frame, a golf ball tee movably supported by said frame for vertical movement through said dispensing chamber to tee up a ball in said chamber and lift it to driving position above said frame, a chute in said frame for delivering a ball to said dispensing chamber, a golf ball feeding chamber in said frame below said chute, a circular track in said frame and extending from said feeding chamber to said chute, a ball lifting arm rotatably mounted in said frame for movement around said track to engage a ball in said feeding chamber and move it around said track to said chute, drive means for rotating said arm, means subject to the presence of a ball in said feeding chamber and the absence of a ball on said tee for operating said drive means, means in said frame for normally lifting said tee to driving position, and means rotatable with said arm for overcoming said lifting means and lowering said tee to said dispensing chamber.

6. A golf ball teeing device which comprises a tee, a support for said tee that is vertically movable between ball loading and ball playing stations, a ball feeding station, a ball feeding member for moving a ball from said feeding station to said loading station, means operative by a ball at the feeding station for moving said feeding member to move the ball to said loading station, means operated by the weight of a ball on said tee for stopping the operation of said feeder member moving means, and means periodically operable by said feeder member moving means for overcoming the operation of said weight influenced stopping means when said tee is carrying a ball from the loading station to the playing station.

7. A golf ball teeing mechanism which comprises a tee that is movable between a ball-loading station and a ball-playing station, a ball-feeding station, a ball-feeding member for moving a ball from said ball-feeding station to said ball-loading station, means operative by a ball at the feeding station for moving said feeding member to move the ball to said loading station, means subject to the weight of a ball on said tee to control the operation of said member moving means, a remote operator's station, electrically operated means including an electric circuit for indicating at the tee and at said operator's station the number of balls in a series which have been fed to said loading station and tee, and a switch controlling said electric circuit and actuated by the operation of said member moving means for actuating said electrically operated indicating means.
